FRAME AND OPERATING MECHANISM FOR CIRCUIT BREAKERS

Edwin C. Goodwin, Jr., Canton, Mass., assignor to Allis-Chalmers Manufacturing Company, Milwaukee, Wis.

Filed July 17, 1962, Ser. No. 210,341

18 Claims. (Cl. 200—153)

This invention relates to a circuit breaker structure and more particularly to a new and improved frame and circuit breaker operating mechanism for opening and closing a pair of arcing contacts.

In the low voltage circuit breaker structures of the conventional type with links, cranks and other mechanism placed within a relatively heavy box type frame, it has been necessary to rigidly attach this frame to cooperating structure which supports the primary electrical contacts. The heavy box type frame and the necessary welding joints, multiple bolting, etc. of the box to the cooperating switchgear structure rendered this mechanism highly inaccessible for servicing, repairing or maintenance of the component parts thereof. Further the box type frame structure resulted in a frame geometrical configuration which incorporated unnecessary metal thickness and weight.

In accordance with the invention disclosed a new and improved circuit breaker structure is provided for use with, but not limited to, low voltage air circuit breakers of the 600 volt class. This new structure is an improvement over the prior art in that it places the operating mechanisms (the components) outside a single center plate type support frame where they are readily accessible for inspection, adjustment, cleaning and lubricating. This accessibility feature is of prime importance in the maintenance of protective equipment of this type. Further, it permits the use of a minimum number of parts of minimum size and complexity. This is accomplished by a structural design which effectively relates the stresses imposed by the breaker operation to the placement of frame components. Component sections and fastening means are reduced to the ultimate minimum.

The new and improved placement of the circuit breaker components provides adequate protection for all of the parts involved as well as protecting personnel against accidental involvement therewith. Still further, the use of a minimal size structural component allows added space adjacent to the breaker structure for the placement of control components such as static overcurrent trip devices, relays, auxiliary switches and so forth which the present day breaker structures employ. The single center plate mechanism support of the disclosed structure increases the space adjacent the primary conducting means, thus facilitating inspection and maintenance as well as radiational cooling. The center plate mechanism support is not susceptible to transient strain during operation, which condition could cause displacement between cooperating parts of the circuit breaker operating mechanism.

In accordance with the invention claimed a circuit breaker structure is provided comprising in combination a frame having a leg member and a cross member extending laterally from the leg member. The leg member may be considered the single center plate mechanism support disclosed above. At least one relatively stationary contact is mounted on the cross member. A shaft is set forth as being rotatably mounted on the leg member and is arranged to extend laterally therefrom. At least one relatively movable contact is mounted on the shaft for cooperation with the stationary contact. Means are mounted on the leg member for actuating the shaft to open and close the contacts. The forces resulting from the opening and closing of the contacts are set forth as being coplanar.

It is, therefore, one object of this invention to provide

2

a new and improved contact controlling mechanism for a circuit breaker structure.

Another object of this invention is to provide a new and improved frame structure for a circuit breaker mechanism.

A further object of this invention is to provide a new and improved frame and contact controlling mechanism wherein the forces resulting from opening and closing of the contacts are all coplanar.

10 A still further object of this invention is to provide a new and improved frame and contact controlling mechanism wherein the sum of the stresses from the opening and closing the contacts is zero.

15 A still further object of this invention is to provide a new and improved low voltage air circuit breaker structure wherein the forces resulting from the opening and closing of contacts employing rotary motion converted into linear motion are arranged coplanar with one portion of the frame structure.

20 A still further object of this invention is to provide a new and improved structural design which effectively relates the stresses imposed by circuit breaker operation to the placement of frame components.

25 A still further object of this invention is to provide a new and improved circuit breaker frame structure employing a single plate for supporting all of the contact actuating mechanisms.

30 A still further object of this invention is to provide a new and improved frame and circuit breaker operating mechanism employing a minimum number of parts of minimum size and complexity which are simple to construct and dependable and easily maintained.

35 Objects and advantages other than those set forth will be apparent from the following description when read in connection with the accompanying drawings in which:

FIG. 1 is a side elevation with parts broken away illustrating a circuit breaker structure utilizing a transmission mechanism employing the present invention and showing the contact closing and opening springs in their unbiased and biased positions, respectively.

FIG. 2 is a side elevation with parts broken away similar to that illustrated in FIG. 1 wherein the closing springs are shown charged and the opening spring discharged;

40 FIG. 3 is an isometric view partly in section of the frame structure shown in FIGS. 1 and 2;

FIG. 4 is a cross sectional view of the structure shown in FIG. 1 taken in the direction of the arrows IV—IV;

FIG. 5 is a top view of the frame structure shown in FIG. 3 illustrating the placement of the relatively movable and stationary arcing contacts;

FIG. 6 is a front view of the circuit breaker frame structure shown in FIG. 3;

50 FIG. 7 is a diagram illustrating the components of the coplanar forces superimposed on the top view shown in FIG. 5 with the components individually identified;

FIG. 8 is an isometric view of a simplified version of the frame structure shown in FIG. 3 illustrating another view of the coplanar forces with the components individually identified;

60 FIG. 9 is a diagram illustrating the coplanar force components superimposed on a side elevational view similar to that shown in FIGS. 1 and 2;

FIG. 10 is a diagram showing the resultant of the forces illustrated in FIG. 9; and

65 FIG. 11 is a diagram illustrating the coplanar force components as superimposed on a view similar to that shown in FIG. 4.

Referring more particularly to the drawings by characters of reference FIGS. 1 through 6 illustrate a circuit breaker 10 employing a single center plate mechanism support frame 12. Frame 12, as more clearly shown in

FIG. 3, comprises a T-shaped construction employing a single frame leg member 13 attached to a back plate or cross member 14 which extends laterally from the leg member 13. The leg member 13 may be attached in any suitable way to the cross member 14 such as by welding, bolting and so forth or it may be formed with cross member 14 out of one piece of material. Although the frame is formed of a metal any suitable plastic material may be used.

The leg and cross members 13 and 14 of the T-shaped frame are mutually braced by side rails 15 and 16 and an apron 17. Because the T-shaped frame provides a means for symmetrical, balanced placement of the circuit breaker operating mechanism around the leg member 13, the rails 15, 16 are subjected only to the tension stress of the toggle 61 (FIG. 1) thereby requiring only a minimum of material weight and strength.

Leg member 13 is formed of two flanged pieces 18 and 18' arranged in juxtaposition with their flat surfaces 19, 19' adjacent each other and their flanged reinforcing edges 20, 20' extending laterally from the flat surfaces outwardly of each other as shown in FIG. 3. At the free end of leg member 13 reinforcement blocks of metal 21 are attached to surfaces 19, 19' and are so formed to provide a cavity 22 extending through the flange surfaces at the free end of the leg member (as shown) for receiving parts of the circuit breaker operating mechanism 28, hereinafter described.

As noted from the drawings and particularly FIG. 3 thereof the cross member 14 is provided with apertures 23, 24 and a flange edge 25 which extends outwardly of the flat surfaces 26 of cross member 14 toward the leg member 13. A piece of insulating material 27 is mounted on cross member 14 between flange edge 25 with cleats 30 and 31 extending through apertures 23 and 24, respectively, for supporting the current conducting elements on bus bars 32 and 33 of the energizing circuit.

Circuit breaker 10 utilizes a transmission mechanism 35 for actuating an arcing contact controlling mechanism 36. The transmission mechanism 35 comprises a pin 37 having rotatably mounted thereon a cam 38. Cam 38 is rotated by a manually rotatable handle 39. Pin 37 extends through cavity 22 of leg member 13 and is rotatably mounted on metal blocks 21. Cam surface 38 is arranged to extend within cavity 22 and upon rotation thereof drives a cam roller 40. Cam roller 40 is mounted within cavity 22 on a pin 41. Pin 41 extends through cavity 22 with the ends thereof loosely mounted in kidney-shaped slots 42, one of which is formed in each of the surfaces of the metal blocks 21. A pair of links 44 (one of which is shown in FIGS. 1 and 2) are pivotally mounted on pin 41 one at each end of pin 41 between slots 42 and the ends of the pin on each side of leg member 13. The other ends of links 44 are pivotally connected one to each end of a pin 45. Pin 45 is arranged to extend within aligned slots 46 formed in the adjacent surfaces 19, 19' of leg member 13. A pair of resilient rollers 47 are mounted on pin 45 one at each end thereof and come to rest at the bottom of slot 46 against the top of metal blocks 21 mounted on the outside of surfaces 19, 19'. To the ends of pin 45 is fixedly attached a pair of tension springs 50 one arranged on each side of leg member 13. The other ends of springs 50 are fixedly attached to leg member 13 at point 51. Thus, upon counterclockwise rotation of handle 39, cam 38 forces roller 40 upwardly along the kidney-shaped slot 42 causing the upward movement of pin 45 and link 44 causing a tensioning or charging of spring 50. A spring biased prop latch 49 bears against roller 40 mounted on pin 41 and holds springs 50 in this charged position.

A pair of closing cams 52 having cam surfaces 52' are pivotally mounted between the ends thereof one at each end of a pin 53. Pin 53 is mounted to extend through and be supported by metal blocks 21 on surfaces 19, 19' of leg member 13. One end of each of

the closing cams 52 is pivotally mounted at different ends of pin 41 outside of the surfaces of block 21. Thus, as pin 41 is pushed upwardly in kidney slots 42, cams 52 are pivoted clockwise about pin 53.

As shown in FIGS. 1 through 6 the arcing contact mechanism 55 includes three pair of cooperating contacts 55a, 55b, 55c and 56a, 56b, 56c. The relatively stationary contacts 56a, 56b and 56c are mounted on the cross member 14 with the stationary contact member 56b mounted on cross member 14 substantially within the plane of leg member 13. Contact members 56a and 56c are mounted one on each side of contact 56b. The relatively movable contacts 55a, 55b and 55c are actuated by shaft 72 through toggles 61 to cooperate with the stationary contacts with contact 55b being mounted substantially within the plane of leg member 13 and contacts 55a and 55c being mounted one on each side symmetrically of leg member 13. In FIG. 1 the contacts are shown in contact closed position before the stored energy springs 50 are charged by counterclockwise rotation of handle 39. FIG. 2 shows the contacts in contact open position after the stored energy springs 50 have been charged.

The contact controlling mechanism comprises cooperating overcenter toggle 60 and an offcenter toggle 61. Each toggle arm comprises a pair of spaced parallelly arranged arm members as shown in FIG. 4, however, for purposes of simplification each toggle arm is referred to as a single member. Toggle 60 comprises a pair of toggle arms 62 and 63 interconnected at adjacent ends by a toggle roll 64. Toggle roll 64 is acted upon by closing cam 52. The free end of toggle arm 62 is pivotally mounted in a kidney-shaped slot 65 in leg member 13. Bell crank 66 is pivotally mounted at 67 on leg member 13 and is biased in a counterclockwise direction by a spring 68. The free end of toggle arm 63 is pivotally connected to the knee of toggle 61. Toggle 61 comprises a pair of toggle arms 70 and 71. Toggle arm 70 is fixedly mounted on a shaft 72. Shaft 72 is rotatably attached to the ends of apron 17. Toggle arm 71 is pivotally attached to the movable arcing contact 55. As shown in FIGS. 1 and 2 the center movable contact structure 55b of the three phase system is shown wherein the knee of toggle 61 is directly connected to the end of toggle arm 63. The movable contact structures 55a and 55c of the other two phases each employ a toggle 61 which is directly connected through toggle arm 70 to shaft 72 and are actuated thereby. Only the center phase of the three phase system has the knee of its toggle 61 connected to the end of toggle arm 63 of toggle 60.

A pair of contact opening tension springs 75 are connected one at each end to flanges 76 fixed to shaft 72. The other end of springs 75 are connected to the circuit breaker frame structure at 77.

With the circuit breaker in open position as shown in FIG. 2, the cooperating toggles 60 and 61 are in their collapsed positions. This collapsed condition is maintainable when the stored energy closing springs 50 are charged since in this condition the closing cam 52 is down and out of the way and cam roller 64 at the knee of toggle 60 can collapse to the left counterclockwise as the breaker contacts open. This function is dependent on releasably restrained connection of toggle arm 62 to the slot 65 and bell crank 66 through pin 78.

With the toggles 60 and 61 collapsed as shown in FIG. 2 and springs 50 charged, roller 64 on the knee of toggle 60 moves along the cam surface of closing cam 52. Spring biased prop latch 49 bears against roller 40 and holds springs 50 in their charged condition. With the release of latch 49 by downward pressure as shown in FIG. 2 closing cam 52 is rotated counterclockwise driving the roller 64 and the knee of toggle 60 to its overcenter position against a resiliently cushioned stop 80. This motion effects movement of toggle 61 to close the arcing contacts.

Closure of the arcing contacts results in charging of the

contact opening springs 75. A component of the opening reaction of springs 75 results in a clockwise rotational bias of bell crank 66. This rotation is controlled by rotary latch 83. Latch 83 comprises a notched pin 84. Clockwise rotation of bell crank 66 causes an edge 85 thereof to be biased against latch 83. A small rotation of latch 83 by the inward movement of release rod 86 releases bell crank 66 and the force of springs 75 revolves bell crank 66 clockwise. The knee of toggle 60 rides vertically downward along the face of the stop 20. Pin 78 at the free end of toggle arm 62 rides downwardly in slot 65 in frame member 13. This downward vertical motion of toggle 60 causes collapse of toggle 61 and opening of the arcing contacts. This action may occur even though closing cam 52 is in the up or spring discharged position shown in FIG. 1.

Rotation of cam 52 away from stop 87 to the charged position of springs 50 as previously described will permit toggle 60 to collapse to the left under the toggle collapsing influence of the toggle breaking spring 81. Thus, the toggle linkage 60 is again in position for a reclosure of the contacts.

A description of the circuit breaker operation is as follows: with the circuit breaker in the open position as shown in FIG. 2 with the arcing contacts 55 and 56 open the double toggles 60 and 61 formed by toggle arms 62, 63 and 70, 71, respectively, are collapsed. This collapsed condition can be maintained only when the stored energy closing springs 50 are charged by counterclockwise rotation of a handle 39. This rotation of handle 39 causes the clockwise movement of closing cam 52 to a position where the knee of toggle 60 can collapse to the position shown in FIG. 2.

To close the arcing contacts of the circuit breaker, toggle 60 must be moved to its overcenter position. This is accomplished by moving downwardly trip latch 49 which releases pin 41 for movement downwardly in slot 42 and under the action of the bias of springs 50 causes closing cam 52 to rotate counterclockwise to move the toggles 60 and 61 thereby closing the arcing contacts 55 and 56. This position is shown in FIG. 1.

A component of a previous opening reaction provided by accelerating contact opening springs 75 results in a clockwise rotation component of bell crank 66. This rotation is controlled by latch 83.

Opening of the arcing contacts occurs upon a small rotation of shaft 34. This occurs upon the inward movement of rod 86 as shown in FIGS. 1 and 2. The previously referred to force component acting on latch 83 by bell crank 66 revolves bell crank 66 and causes toggle 60 to ride vertically downward along cam face 82 of toggle breaking spring 81. This vertical motion of toggle 60 causes toggle 61 to collapse and the circuit breaker to open even though cam 52 is in the up or spring discharged position shown in FIG. 1. Rotation of cam 52 to the charged position by handle 39 previously described allows toggle 60 to collapse to the left under the influence of toggle breaking spring 81 which bears against the toggle knee. The linkage comprising toggles 60 and 61 are again in a position for a reclosure operation.

FIGS. 7 through 11 illustrate the force components of the operating mechanism. These force components in some of the figures are superimposed upon the circuit breaker frame structure to clearly illustrate the effective and advantageous combining of the forces coplanarly. In these figures the individual force components are shown as a beam or column in equilibrium. No stresses imposed by the support of the breaker in the cubicle are a part of this analysis since they are of a decidedly secondary nature.

Since the purpose of this analysis is to describe the type and direction of the stresses imposed by the breaker in operation, all views and diagrams are shown with the breaker in the closed position. The abbreviation MMR stands for magneto-mechanical reaction and is defined as

the algebraic total of the magnetic forces and the mechanical springs, accelerating springs, etc. The reference characters identify the same part in each of the figures.

As noted in FIG. 7, shaft 72 is supported by the side rails 15 and 16. Three concentrated loads are shown with one on the center line through leg member 13 and two symmetrically located about the center line of leg member 13 along toggle 61 in phases A and C. Toggle arms 70 and 71 of toggle 61 are loaded in compression.

While the primary copper is designated as a single element in each phase, for purposes of this analysis the primary copper comprises the cooperating members of the arcing contacts, namely the main and arcing contacts of the movable contacts 55, the stationary contacts 56, and the primary bus conductors 32 and 33.

The cross member 14 which serves as the base of the T-shaped frame structure is supported upright at both ends by rails 15 and 16. Three concentrated loads are applied to the primary copper as shown, one on the center base of leg member 13 and two symmetrically located about the center line. These loads are the MMR reactions per phase.

The stress in side rails 15 and 16 is essentially pure tension since it is located in the plane of toggle arms 70 and 71 of toggle 61, note FIG. 9. The effective tension stresses in the side rails is not substantially different as the breaker closes. When the circuit breaker is in normal operation, the MMR loads imposed at phases A, B and C are accepted equally by the side rails 15 and 16. The extreme condition of the side rail loading is encountered when the maximum current is reached in either one of the outer phases A or C. Under this condition, the side rails 15 and 16 adjacent to the maximum current phase receives a higher tension stress.

Since all of the stresses imposed by the MMR loads (except vertical toggle component load R FIGS. 9 and 10) are completely contained within a parallelogram formed by shaft 72, side rails 15 and 16 and cross member 14, the mechanism frame is isolated from any external stresses and thus its reactions need not exceed those required by the stresses imposed by the operating mechanism. This condition is illustrated by FIG. 8.

In FIG. 9 the force diagram illustrates the vertical toggle arms 62 and 63 of toggle 60 loaded in compression. The trip latch 66 is shown loaded in compression and is releasably restrained by pin 84 of latch 83. Pin 84 is supported in the middle by leg member 13 and two concentrated loads are symmetrically located about its middle support or bearing.

Since the leg member 13 comprising the mechanism frame is fastened to cross member 14 at point E and through side rails 15, 16 and apron 17 at point D it becomes in essence a beam supported at both ends with a single concentrated load R unsymmetrically placed. This is more clearly noted from FIG. 10. The value R is determined by the off-center setting of toggle arms 70 and 71 and is limited to a very nominal value with the circuit breaker closed in order to keep the required tripping force at a minimum. It is noted that during the closing cycle the resultant force R reaches a somewhat higher transient value due to the changing toggle arm angles. Thus, the fastenings which support the mechanism frame are of minimum size and quantity as they are required to resist only the nominal shear stresses imposed by load R.

FIG. 11 illustrates diagrammatically the forces on the vertically arranged leg member 13 of the T-shaped frame. The toggle pin 88 interconnecting toggle arms 70 and 71 of toggle 61 and the end of toggle arm 63 of toggle 61 is supported at both ends with two symmetrically placed concentrated loads. The toggle pin 88 connecting together toggle arms 62 and 63 of toggle 60 and supporting toggle roll 64 is supported at both ends having two symmetrically placed concentrated loads. Toggle pin 78 connecting toggle arm 62 to bell crank 66 is also supported

at both ends and has two symmetrically placed concentrated loads.

The external loading applied to the mechanism frame by the vertical toggle component load R is transmitted to the frame through symmetrically disposed vertical toggle arms 62 and 63, toggle pins 88, 89 and 78 and trip rod 84. Since the frame is not subjected to torque stresses in the lateral plane due to unsymmetrically applied loads, the lateral stiffness of the frame can be held to the minimum required to support the operating mechanism.

Thus, the resultant forces for opening and closing of the contacts and the charging of springs 50 and 75 are substantially coplanar or parallel with the leg frame member 13 of the circuit breaker structure. Further, the sum of the stresses resulting from opening and closing of the contacts is substantially zero.

Although but one embodiment of the present invention has been illustrated and described it will be apparent to those skilled in the art that various changes and modifications may be made therein without departing from the spirit of the invention or from the scope of the appended claims.

Having now particularly described and ascertained the nature of my said invention and the manner in which it is to be performed, I declare that what I claim is:

1. A circuit breaker structure comprising in combination a frame having a single leg member and a cross member extending laterally from said leg member, a relatively stationary contact mounted on said cross member, a shaft rotatably mounted on said leg member and extending laterally therefrom, a relatively movable contact mounted on said shaft for cooperation with said stationary contact, and means mounted on said leg member for actuating said shaft to open and close said contacts, the forces resulting from opening and closing of said contacts being substantially coplanar with each other.

2. A circuit breaker structure comprising in combination a frame having a leg member and a cross member extending laterally from said leg member, a relatively stationary contact mounted on said cross member substantially within the plane of said leg member, a shaft rotatably mounted on said leg member and extending laterally therefrom, a relatively movable contact mounted on said shaft for cooperation with said stationary contact, and means mounted on said leg member for actuating said shaft to open and close said contacts, the forces resulting from opening and closing of said contacts being substantially coplanar with each other.

3. A circuit breaker structure comprising in combination a frame having a leg member and a cross member extending laterally from said leg member, a relatively stationary contact mounted on said cross member substantially within the plane of said leg member, a shaft rotatably mounted on said leg member and extending laterally therefrom, three movable contacts mounted on said shaft for cooperation with said stationary contact, and means mounted on said leg member for actuating said shaft to open and close said contacts, the forces resulting from opening and closing of said contacts being substantially coplanar with said leg member.

4. A circuit breaker structure comprising in combination a frame having a leg member and a cross member extending laterally from said leg member, a pair of relatively stationary contacts spacedly mounted on said cross member, a shaft rotatably mounted on said leg member and extending laterally therefrom, a pair of movable contacts mounted on said shaft one cooperating with each of said stationary contacts, and means mounted on said leg member for actuating said shaft to open and close said contacts, the resultant of the forces for opening and closing said contact being substantially coplanar with said leg member.

5. A circuit breaker structure comprising in combination a frame having a leg member and a cross member

extending laterally from said leg member, a pair of relatively stationary contacts spacedly mounted on said cross member one on each side of said leg member, a shaft rotatably mounted on said leg member and extending laterally therefrom, a pair of movable contacts mounted on said shaft one cooperating with each of said stationary contacts, and means mounted on said leg member for actuating said shaft to open and close said contacts, the resultant forces for opening and closing said contacts being substantially coplanar with said leg member.

6. A circuit breaker structure comprising in combination a frame having a leg member and a cross member extending laterally from said leg member, a pair of relatively stationary contacts spacedly mounted on said cross member one on each side of said leg member, a shaft rotatably mounted on said leg member and extending laterally therefrom, a pair of movable contacts mounted on said shaft one cooperating with each of said stationary contacts, and means mounted on said leg member for actuating said shaft to open and close said contacts, the resultant forces for opening and closing said contacts being substantially parallel to said leg member.

7. A circuit breaker structure comprising in combination a T-shaped frame having a leg member and a cross member extending laterally from said leg member, three relatively stationary contacts spacedly mounted on said cross member, one of said stationary contacts being mounted substantially within the plane of said leg member and the other two of said stationary contacts being mounted one on each side of said leg member, a shaft rotatably mounted on said leg member and extending laterally therefrom, three movable contacts mounted on said shaft one cooperating with each of said stationary contacts, and means mounted on said leg member for actuating said shaft to open and close said contacts, the resultant forces for opening and closing said contacts being substantially parallel with said leg member.

8. A circuit breaker structure comprising in combination a T-shaped frame having a leg member and a cross member extending laterally from said leg member, three relatively stationary contacts spacedly mounted on said cross member, one of said stationary contacts being mounted substantially within the plane of said leg member and the other two of said stationary contacts being mounted one on each side of said leg member, a shaft rotatably mounted on said leg member and extending laterally therefrom, three movable contacts mounted on said shaft one cooperating with each of said stationary contacts, and means mounted on said leg member for actuating said shaft to open and close said contacts, the resultant forces for opening and closing said contacts being substantially parallel with said leg member.

9. A circuit breaker structure comprising in combination a T-shaped frame having a leg member and a cross member extending laterally from said leg member, three relatively stationary contacts spacedly mounted on said cross member, one of said stationary contacts being mounted substantially within the plane of said leg member and the other two of said stationary contacts being mounted one on each side of said leg member, a shaft rotatably mounted on said leg member and extending laterally therefrom, three movable contacts mounted on said shaft one cooperating with each of said stationary contacts, and means mounted on said leg member for actuating said shaft to open and close said contacts, the resultant forces for opening and closing of said contacts being coplanar with each other.

10. A circuit breaker structure comprising in combination a frame having a leg member and a cross member extending laterally from said leg member, a relatively stationary contact mounted on said cross member, a shaft rotatably mounted on said leg member and extending laterally therefrom, a relatively movable contact mounted on said shaft for cooperating with said stationary contact, spring means mounted on said leg member for clos-

actuating said shaft to open and close said contacts, the sum of the stresses resulting from opening and closing of said contacts being substantially zero.

18. A circuit breaker structure comprising in combination a T-shaped frame having a leg member and a cross member extending laterally from said leg member, three relatively stationary contacts spacedly mounted on said cross member, one of said stationary contacts being mounted substantially within the plane of said leg member and the other two of said stationary contacts being mounted one on each side of said leg member, a shaft rotatably mounted on said leg member and extending laterally therefrom, three movable contacts mounted on

5

10

said shaft one cooperating with each of said stationary contacts, and means mounted on said leg member for actuating said shaft to open and close said contacts, the resultant stresses for opening and closing of said contacts being substantially zero.
